UNITED STATES PATENT OFFICE

2,062,753

ROTARY GASOLINE ENGINE

Albert W. Linn, Memphis, Tenn.

Application November 9, 1934, Serial No. 752,293

2 Claims. (Cl. 123—13)

This invention relates to rotary internal combustion engines comprising a stationary enclosing casing, sections of which in planes perpendicular to the axis of the engine are circular, and a 5 rotating element or rotors, with a piston or vane therein, together with an element, designated "an abutment" movable in itself, but fixed relative to the rotary movement of the vane; said casing, abutments, and a portion of the vane enclosing 10 an annular spacing chamber within which the burned gases are closed and permitted to act expansively thereby impelling the piston.

The primary object of this invention is to provide a device of this kind in which a substantially 15 similar structure is associated to act as a compressor for furnishing combustion products to the firing chamber, the rotor, vane and abutment of such compression chamber being respectively coordinated with and caused to move with the 20 complementary parts in the firing chamber.

A further object is to simplify and improve the design of such a structure:—

The means by which these and other objects are accomplished and the manner of their accomplishment will be readily understood from the following specification on reference to the 25 accompanying drawing, in which:—

Fig. 1 is a vertical sectional elevation through the combustion chambers and at right angles to 30 the axis of the rotary parts, taken as on the line I—I of Fig. 2, showing relation of the parts at the end of expansion and just prior to admitting and firing a new charge.

Fig. 2 is a sectional plan taken as on the line 35 II—II of Fig. 1.

Fig. 3 is a vertical sectional elevation complementary to Fig. 1 taken as on the line III—III of Fig. 2 showing the compressor side of the casing and the compressor parts thereof, the timing period being identical with that shown in 40 Fig. 1.

Fig. 4 is a section taken as on the line IV—IV of Fig. 3.

Fig. 5 is a section identical with Fig. 1 except 45 that it shows the relation of the parts during expansion.

Fig. 6 is a section similar to Fig. 3, except for timing which conforms to Fig. 5, and is during intake and compression strokes.

Fig. 7 is a plan view of the device on a slightly 50 reduced scale, and

Fig. 8 a corresponding front elevation of the device.

Referring now to the drawings in which the 55 various parts are indicated by numerals, 10 and 11

are respectively cylindrical compressor and combustion chambers preferably of equal diameter, which are separated by a flat division wall 12 in which is journaled a shaft 13 with which both chambers are concentric.

Disposed within the chambers 10 and 11 are cylindrical rotating elements or rotors 14 and 15 of less diameter than the chambers, both elements being mounted on and secured to the shaft 13 as by keys 16 and 17 respectively. These 10 rotors are of equal diameter and are concentric with the shaft and the chambers. Positioned laterally outward on opposite sides of the chamber 10, are cylindrical abutment chambers 18, 19, and on opposite sides of the chamber 11, similar abutment chambers 20, 21 which respectively cut into opposite sides of the chambers 10 and 11, these abutment chambers being precisely one-half the diameter of the rotors 14, 15. The chambers 18 and 20, 19 and 21 are respectively 20 separated by continuations of the wall 12. Mounted in and closely fitting the abutment chambers 18, and 20 respectively, are cylindrical 25 abutments 22, 23, both of which are mounted on and keyed, as by keys 24A, 24B respectively, to a shaft 24 which extends through and is journaled in the wall 12.

Identical abutment members 22A, 23A are disposed in the chambers 19, 21 respectively, these latter abutment members being keyed as by keys 25A, 25B, respectively to the shaft 25. The shafts 13, 24 and 25, are so disposed that the abutment members 22, 22A turn in rolling contact with the related rotor 14, and the abutments 23, 23A with the rotor 15.

The arcuate walls 10A, 18A, and 19A respectively surrounding the compressor chamber 10 and its related abutment chambers 18, 19, are of equal height, with the rotor 14 and the related abutments 22, 22A respectively therein, and the 40 same is true of the arcuate wall 11A of the combustion chamber 11, and the arcuate walls 20A, 21A of the abutment chambers 20, 21 and the rotor 15, and the abutments 23, 23A respectively therein.

26, 27 are respectively cover plates for the compressor and combustion chambers, these plates being pressed against the chamber walls and the rotating members in the chambers by springs 28. Casing covers 29, 30 respectively secured as 50 by bolts 31, hold the springs 28 against the cover plates. 32 are open spaces in the casing walls for the circulation of cooling water.

The rotor 14 is inwardly slotted at 33B, 33C on diametrically opposite sides to receive com- 55

plementary vanes 33, 33A; and the element 15 is similarly slotted at 34B, 34C to receive similar piston members and 34, 34A. 35 are springs urging the vanes radially outward. The 5 outer end of each vane, as the vane 34, is arcuately convex and each complementary abutment, as the abutment 23, is provided with an arcuate depression 24B adapted to closely embrace the convex portion of the vane. The depth of the 10 arcuate depression in each abutment is such that the outer end of the convex end of the vane lies in the circle formed by a continuation of the cylindrical wall 11A or 10A of the chamber 11, or 10, as the case may be. Each of the vanes, 15 as the vane 34, is provided with a shoulder 36 at the rear side of the vane, as it turns in its chamber which shoulder contacts the peripheral surface of the abutment 23, and prevents the vane from being forced too far outward as it 20 moves into engagement with the circular wall of the chamber.

The vanes 34, 34A in the combustion chamber 11 are cut away at 37 and the abutments 23, 23A in such chamber are under-cut as at 38, so 25 that they may properly uncover ports 39, 39A leading into that chamber.

Movement of the rotors 14—15 and their related abutment members 22—22A, 23—23A, are coordinated by gears 40, 41 and 41A respectively 30 mounted on and keyed as by keys 40A to the shafts 13, 24 and 25, the gear ratio being two to one. 42 is a casing housing the gearing.

From the compression chamber 10, a passageway 50 and a diametrically opposite passageway 50A, lead into firing chambers 51 and 51A in the wall 12, Fig. 3. From these chambers the ports 39, 39A lead into the combustion chamber 11. Each of the passageways 50, 50A, as the passageway 50, is closed against return flow from its 40 related firing chamber to the chamber 10 as by a check valve 52 which is normally held closed as by a spring 53. 54 is a spark plug, Fig. 4.

60 indicates a carburetor which is connected by suitable manifold members 61, 62 to suitable 45 passageways 63, 64 which lead into diametrically opposite portions of the chamber 10. 65, 66 are exhausts leading from diametrically opposite sides of the combustion chamber 11. 67 and 68 indicate piping by which lubricating oil may be delivered to the abutment chambers.

It will also be understood that the details of construction are typical only and are introduced for purposes primarily of illustration.

The operation of the device is as follows:

Assuming the parts in the intake and compression chamber to be positioned as shown in Fig. 3, 55 rotary movement of the rotor 14 and its vanes toward the position shown in Fig. 6 will concurrently move the abutments 22—22A to the corresponding position there shown, and will establish intake chambers under vacuum, respectively between the abutment 22 and the vane 33 and between the abutment 22A and the vane 33A into which firing charges are drawn through the intakes 63—64. This charging movement will continue until the vanes pass the opposite abutment members, after which a second charge will be drawn through the intakes behind the vanes and compression will occur in front of the vanes and 70 the abutments, toward which they are moving; such action continuing until operation of the engine ceases. The combustible gases so compressed in front of the vanes will pass through the openings 50—50A past the check valves 52 into the firing chambers 51—51A, but will be retained from

passage from such firing chambers into the expansion chambers through the openings 39—39A by the abutments 23—23A, Figs. 1 and 5, until the cut away portions, 37 of the vanes, and 20, 21 of the abutments uncover such openings. At such time 5 by proper timing means not shown the charges are fired by the spark plugs 54 and escape through the openings 39, 39A into the annular expansion chambers against the backs of the vanes 34, 34A. Thereafter expansion between the back of the 10 vanes and the abutments 23, 23A, as shown in Fig. 5, will continue impelling the said vanes forward and imparting power impulses to such vanes. Such expansion continues until the vanes last 15 mentioned uncover the exhaust ports 65 and allow the spent charges to escape to the atmosphere, this cycle of operations continuing as long as actuating charges of gas are supplied through the carburetor and intake passages.

What I claim is:

1. In a rotary internal combustion engine, an annular casing, end walls completing a cylindrical enclosure and a division wall dividing said enclosure into two cylindrical compartments, concentric rotors of less diameter than said compartments disposed one in each thereof and forming therewith respectively annular compression and expansion chambers, an annular cylindrical casing intersecting a side of said first casing and enclosing an abutment chamber which intersects said cylindrical enclosure, a closely fitting cylindrical abutment in said abutment chamber, said abutment having an arcuate piston receiving recess therein, said abutment chamber being spaced from said central compartment to hold said abutment in rotary contact with said rotors, shafts journaled in the end walls and division wall of said casing, and having respectively secured thereon said rotors and said abutments, and gearing compelling synchronous movement 30 of said rotors and said abutments; each of said rotors having a piston projecting therefrom adapted to establish sliding contact with the peripheral wall of the said compartment and to engage and fill said abutment recess; said division 40 wall having a firing chamber therein, a passageway leading thereto from said compression chamber adjacent one side of said abutment, said passageway having a check valve therein preventing return flow to said compression chamber; and a passageway leading from said firing chamber to said expansion chamber, said latter passageway being normally closed by said abutment and by said piston therein, the rear portion of 50 said piston in said expansion chamber being cut away to form with the abutment recess complementary thereto, an opening adapted to uncover said latter passageway at a predetermined interval, charge firing means in said firing chamber, inlet means to said compression chamber, and an exhaust passageway from said expansion chamber.

2. In a rotary internal combustion engine, an annular casing, end walls completing a cylindrical enclosure and a division wall dividing said 65 enclosure into two cylindrical compartments, concentric rotors of less diameter than said compartments disposed one in each thereof and forming therewith annular chambers; diametrically opposite annular cylindrical casings intersecting 70 each a side of said first casing and enclosing abutment chambers which intersect opposite sides of said cylindrical enclosure, closely fitting cylindrical abutments one in each said abutment chamber, said abutments having each an arcuate 75

piston receiving recess therein, said abutment chambers being spaced from said compartments to hold said abutment in rotary contact with said rotors, and divide said chambers respectively into 5 two compression and two expansion chambers, shafts journaled in the end walls and division wall of said casings, and having respectively secured thereon said rotors and said abutments, and gearing compelling synchronous movement 10 of said rotors and their respective abutments; each of said rotors having diametrically opposite pistons projecting therefrom adapted to establish sliding contact with the peripheral wall of its said compartment, and to engage and fill said abutment 15 recess, said division wall having two firing chambers therein, passageways leading from said compression chambers into said firing chambers

one into each, each said passageway being adjacent one side of a said abutment, said passageways each having a check valve therein preventing return flow to a compression chamber; and passageways each leading from a said firing chamber to 5 a said expansion chamber, said latter passageways being normally closed by said abutment and by said piston therein, the rear portion of each said piston in said expansion chambers being cut away to form, with the abutment recess complementary 10 thereto, an opening adapted to uncover said latter passageway at predetermined intervals, charge firing means in said firing chambers, inlet means to said compression chambers, and exhaust passageways one from each expansion 15 chamber.

ALBERT W. LINN.
